UNITED STATES PATENT OFFICE

JOHN A. FILBERT, OF CHICAGO, ILLINOIS

COMBUSTION APPARATUS

Application filed June 13, 1927. Serial No. 198,582.

This invention relates to certain novel improvements in combustion apparatus and is specifically directed to improvements in grate construction for burning coal and similar fuels in furnaces and boilers.

It is among the objects of my invention to provide a grate construction in which the air passage to the fuel may be regulated in accordance with the degree of heat intensity desired and also in accordance with the grade and kind of fuel used.

Another object of the invention is to provide a grate construction embodying an arrangement for breaking up clinker formations and thus producing a more complete combustion of the fuel with attendant reduction of ash and incombustible clinkers.

Still another object of the invention is to provide a grate construction which will permit expeditious control of the fire and therefore permit the usage of a relatively shallow fire.

A further object of the invention is to provide a grate construction from which the fire may be quickly removed when so desired.

Grates of the prior art have had relatively large openings therein and when a fire was being laid it was difficult to prevent small particles of fuel from falling through these openings.

In view of this it is a further object of my invention to provide a construction in which the magnitude of the openings in the grate may be regulated so that they may be substantially closed during the laying of a fire, in order to obviate this just described difficulty.

A still further object of the invention is to provide a grate construction in which certain parts may be moved relative to each other, and which will be mounted in such a way that a high leverage will be provided, which will permit movement of these parts with very little exertion.

A still further object of the invention is to provide such a grate construction which will be simple in construction and economical to manufacture.

Other objects will appear hereinafter.

The invention consists in the novel com-

bination and arrangement of parts to be hereinafter described and claimed.

The invention will be best understood by reference to the accompanying drawings, showing the preferred form of construction and in which:

Fig. 1 is a plan view of the bottom side of my improved grate with the bar rocking mechanism partially removed;

Fig. 2 is a sectional view taken substantially in the plane of the line 2—2 of Fig. 1;

Fig. 3 is a side elevational view of my improved grate construction;

Fig. 4 is a sectional detail view taken substantially in the plane of the line 4—4 on Fig. 1;

Fig. 5 is a fragmental plan view of the top side of my improved grate;

Fig. 6 is a sectional detail view taken substantially in the plane of the line 6—6 on Fig. 1;

Fig. 7 is a detail view of the link construction viewed from the opposite direction to Fig. 2; and

Fig. 8 is a detail view of a clinker cutting device employed in the mechanism.

My improved form of grate construction is adapted to be mounted in the fire box of any type of solid fuel burning apparatus such as furnaces, stationary, and locomotive boilers. As the following description proceeds it will become apparent that I am describing here a section of the grate, and it is to be understood that one or more of these sections would be provided in the fire box, dependent upon the size thereof.

These grate sections comprise a substantially rectangular frame 10 that is adapted to be located within the fire box. This rectangular frame 10 comprises side members 11 and 12 and end members 13 and 14. Suitably secured to the frame 10 is a section 15 which is adapted to be positioned extraneous of the fire box and on which certain operating mechanisms to be described more fully herein-after, are mounted.

Referring to Fig. 3 it may be seen that the side members are provided with a plurality of slots such as 16 which embody a straight portion which terminates in a rounded por-

tion. Adapted to be supported by the side members and having portions extending through these slots are the grate members 17 which have unitary oppositely extending bosses 18 formed on the ends thereof that are adapted to fit into the recesses 16. The straight portions of the slots 16 are of smaller size than the rounded portions thereof and therefore the annular bosses 18 are arranged 10 so as to embody a flat portion 19 which is disposed parallel to the extent of the grate members 17. The purpose of this flat portion 19 is that, when the grate members 17 are to be inserted into the device, they will be turned so that their upper face will be in 15 a substantially vertical plane and therefore, as they are inserted into the slots, the bosses 18 will pass through the straight portions of the slot 16, the side 18 being cut away sufficiently to permit this. However, after the 20 grate members are in their proper position and are rotated so as to be located in a horizontal plane the bosses 18 will be wider than the straight portions of the slot 16 and therefore the grate members 17 will be prevented 25 from moving from their position.

Referring to Fig. 6, it may be seen that the grate members 17 each have a downwardly protruding boss 20 formed thereon in juxtaposition to one end thereof. A connecting bar 21 having upwardly protruding bosses 22 is provided. The upper ends of the bosses 22 are secured to the lower ends of the bosses 20 in any approved manner such as by the 30 bolt and nut construction 23, said construction being such that a pivotal connection is established. The section 15 embodies a downwardly protruding section 24 which is disposed on the same side of the device as the connecting bar 21 and bosses 20. Pivoted 35 secured to the section 24 is a lever 25 that has a portion which extends through a slot 26 in the member 15. Disposed for cooperation with the lever 25 is a segment 27 which 40 has a slot 28 formed therein through which the pin 29 extends, said pin 29 being carried on the lever 25, this construction serving to limit the movement of the lever 25. A connecting rod 30 connects the lever 25 to the 45 connecting bar 21 so that movement of said lever will be transmitted to said connecting bar and therefore to the grate members 17.

A removable handle 31 is provided which is adapted to be fitted onto the end of the 50 lever 25. By moving the lever 25 back and forth through the slot 26 the grate members 17 are caused to rock about the bosses 18 mounted in the slot 16 thus providing a means for removing ash from the fire and 55 also providing an arrangement whereby the fire may be expeditiously dumped.

As is shown best in Figs. 1 and 5 the grate members 17 are formed so as to embody a longitudinal slot 32 and opening into this 60 slot are a plurality of transversely extending

slots 33. Adapted to pass through the slots 32 and 33 is a clinker cutting member 34 which is shaped similarly to the slots 32 and 33 but which is of smaller size than said slots so that said clinker cutting member 70 may be passed through the grate member 17.

Unitary with the end members 13 and 14 are downwardly protruding sections 35 and 36. The members 35 and 36 support rails 37 and 38 at their lower ends, said rails being 75 co-extensive with the length of the grate. As can best be seen by referring to Fig. 2 the rail 38 embodies a plurality of upwardly protruding bosses 39 in which the slots 40 are provided, a similar construction being 80 provided on the rail 37. The rails 37 and 38 are so positioned that the bosses 39 on these rails are in alignment. Pivoted 85 mounted in the slots 40 are the link members 41 and pivotally secured to the outer end of these link members 41 are the link members 42. As is best shown in Fig. 4 downwardly protruding bosses 43 are provided on the under side of the clinker cutting members 34 and the ends of the links 42 are pivotally attached to these bosses 43. The links 41 and 42 are pivotally attached 90 together, as stated, and this pivotal mounting is comprised of the rods 45 which extend through the links 41 and 42 at the intersecting 95 points thereof on each side of the device. The links 41 and 42 serve to support the clinker cutting members 34 in proper relation to the grate members 17.

When the grate members 17 are positioned 100 horizontally as best shown in Fig. 2 the clinker cutting members 34 are adapted to pass through the slots 32 and 33 provided therein. A so-called pantograph lever arrangement is provided for moving the members 34 in a manner described. Brackets 46 (Fig. 1) are provided between the rails 37 and 38 and these brackets provide upwardly protruding bosses 47 (Fig. 2). Pivoted 105 mounted in the bosses 47 are the links 48 and 49. Downwardly protruding bosses 50 (Fig. 2) are provided on certain of the clinker cutting members 34, the arrangement shown in Fig. 2 being the preferable one and links 51 and 52 are pivotally attached to 110 these bosses. The free ends of the links 49 and 52 are pivotally secured together as at 53 and a link 54 connects these two pivotal connections. The links 51 and 48 are pivotally secured together as at 55 and the link 115 56 connects these two pivotal connections together. A link 57 is secured to the pivotal connection 55 between the links 51 and 48 as indicated at 58 and a link 59 is attached to the pivotal connection 53 between the links 120 49 and 52 as at 60, the other end of the links 57 and 59 being attached to the rocker 61 as at 62 and 63. The rocker 61 is pivotally 125 attached as at 64 to a bracket 65 that is carried by the end member 36 and the section 130

15. As can best be seen in Figs. 3 and 7, the links 57 and 59 are attached to the rocker 61 at opposite ends thereof. Secured to the rocker member 61 is an upwardly protruding 5 arm 66 which protrudes through a slot 67 provided in the section 15. The bracket 65 includes a segment 68 which also protrudes through the slot 67 and a plurality of ratchet teeth 69 are provided on the segment 68 and are adapted to be engaged by the spring urged pawl 70 that is carried on the arm 66. The upper end of the arm 66 is arranged so that the handle 31 may be fitted thereon as said handle is adapted to operate both 15 mechanisms.

With the grate members 17 disposed in the manner shown in Fig. 2 and with the clinker cutting members 34 disposed in the position shown in this figure the handle 31 may be 20 fitted on to the arm 66 and then by withdrawing the pawl 70 from engagement with the ratchet teeth 69, the arm 61 may be moved forwardly. As can be seen by referring to this figure, the link 57 is attached to the 25 upper end of the rocker 61 and to the links 51 and 48 at 58 which is the connection most remote from the rocker 61. The link 59 is attached to the lower side of the rocker member 61 and is connected to the links 49 and 20 52 at 60 which is the connection nearest the rocker 61. Therefore when the rocker 61 is moved forwardly it will tend to spread the links 51 and 52 and 48 and 49 away from each other and will thus cause the clinker cutting 35 members 34 to move down through the slots 32 and 33 and continued movement of the rocker arm 31 will dispose the members 34 in the position shown in Fig. 3. Since all of the members 34 are supported indirectly 40 from the shafts 45 by the links 42, it is apparent that movement of any of the clinker cutting members 34 will be transmitted to the others. Further it is apparent by referring to Fig. 3 that it will be necessary 45 for the members 34 to be disposed in the position shown in this figure in order that the grate members 17 may be rocked in the manner described. By referring to Figs. 1 and 2 it may be seen that the links 51 and 52 are 50 formed in a certain manner in order that they will pass through the slots 33 when the members 34 are moved from the position shown in Fig. 3 to the position shown in Fig. 2 by actuation of the rocker 61.

55 Referring to Fig. 8, it may be seen that the upper side of the bars of the member 34 are rounded with a small radii. After a fire has been laid in the grate and after said fire has been burning for an appreciable time 60 the fuel tends to cake or form a solid mass which is not conducive to efficient combustion. Therefore, in order to break this mass the members 34 are caused to move in the manner described, through the grate members 17 and the rounded edges on these mem-

bers tend to break up the mass or clinker formation and therefore cause more complete combustion.

It is apparent that the relation between the members 34 and the grate members 17 70 can be varied. If the members 34 are positioned in the slots 32 in such a way that they are disposed substantially horizontal with the grate members 17, that is so just the rounded portions thereof protrude through the slots, a substantially flat surface having very small openings will be provided. This arrangement can be expeditiously employed during the starting of the fire to prevent small particles of fuel falling through the 75 openings in the grate. If, however, after a fire has been burning for an appreciable length of time and the heat intensity thereof is not as great as desired, the members 34 can be effectively used to break up the clinker 80 formation in the manner described and they can then be disposed out of engagement with the members 17, thus providing relatively large openings through which a comparatively large quantity of air passes which will 85 of course be conducive to a more rapid combustion and thus produce a hotter fire. By varying the relative position of the members 34 with respect to the members 17, the amount of air or so-called draft through the device 90 can be very expeditiously controlled.

As has been stated heretofore the grate member herein described is adapted to be positioned in a relatively large fire box in sections, and when this is done each of these 100 sections will be individually controlled, which will of course permit a more uniform distribution of the fire bed and therefore more uniform distribution of heat in a boiler or furnace. The manner of mounting these sections is not described herein for this forms 105 no part of my invention and the arrangement of these devices will be readily apparent to anyone skilled in the art.

While I have illustrated and described the 110 preferred form of construction for carrying my invention into effect, this is capable of variation and modification, without departing from the spirit of the invention. I, therefore, do not wish to be limited to the 115 precise details of construction set forth, but desire to avail myself of such variations and modifications as come within the scope of the appended claims.

Having thus described my invention what I claim as new and desire to protect by Letters Patent is:

1. A device of the character stated including a grate frame, grate sections mounted in said frame having openings therein, breaker members of a shape and size substantially similar to the outline of said openings to permit passage of said members through said openings, links having corresponding ends 125 130 135

thereof pivotally connected to said breaker members, means for interconnecting the opposite ends of said links, other links each having corresponding ends pivotally connected at each of the connections of said first named links to said interconnecting means, means for pivotally supporting the opposite ends of said last mentioned links whereby said breaker members will be supported for simultaneous movement through said openings in said grate sections, and means for imparting movement to said breaker members.

2. In a device of the character stated, a grate frame, grate sections mounted in said grate frame having openings therein, breaker members of a size and shape substantially similar to the outline of said openings whereby said members will be passable through said openings, links pivotally connected to the under side of said breaker members and movable in a plane parallel to the extent thereof, other links having one of the ends thereof pivotally connected to supporting means carried by said grate frame, means for interconnecting the other ends of said last mentioned links, means for imparting movement to said breaker members to move said breaker members through said openings, and means for locking said last named means to hold said breaker members in predetermined positions.

3. In a device of the character stated, a grate frame, grate sections mounted in said grate frame having openings therein, breaker members of a size and shape substantially similar to the outline of said openings whereby said members will be passable through said openings, links pivotally connected to the under side of said breaker members and movable in a plane parallel to the extent thereof, other links having one of the ends thereof pivotally connected to supporting means carried by said grate frame, means for interconnecting the other ends of said last mentioned links, arms pivotally connected to certain of said grate sections and movable in a plane substantially at right angles to the extent of said sections, other arms pivotally connected to said supporting means, means for interconnecting the other ends of said last mentioned arms, and means for imparting movement to said last mentioned arms to move said breaker members toward and through the openings in said grate sections.

4. In a device of the character stated, a grate frame, grate sections mounted in said grate frame having openings therein, breaker members of a size and shape substantially similar to the outline of said openings whereby said members will be passable through said openings, links pivotally connected to the under side of said breaker members and movable in a plane parallel to the extent thereof, other links having one of the ends thereof

pivotally connected to supporting means carried by said grate frame, means for interconnecting the other ends of said last mentioned links, arms pivotally connected to certain of said grate sections and movable in a plane substantially at right angles to the extent of said sections, other arms pivotally connected to said supporting means, means for interconnecting the other ends of said last mentioned arms, links for interconnecting the interconnections between said last mentioned arms including arms extending beyond said frame, and means connected to said last named links for imparting movement thereto whereby movement may be transmitted through said arms to certain of said breaker members whereby movement will be transmitted through said links to the other of said breaker members to cause said breaker members to be simultaneously moved relative to and through said openings.

5. In a device of the character stated, a grate frame, grate sections mounted in said grate frame having openings therein, breaker members of a size and shape substantially similar to the outline of said openings whereby said members will be passable through said openings, links pivotally connected to the under side of said breaker members and movable in a plane parallel to the extent thereof, other links having one of the ends thereof pivotally connected to supporting means carried by said grate frame, means for interconnecting the free ends of said last mentioned links, arms pivotally connected to certain of said grate sections and movable in a plane substantially at right angles to the extent to said sections, other arms pivotally connected to said supporting means, means for interconnecting the other ends of said last mentioned arms, links for interconnecting the interconnections between said last mentioned arms including arms extending beyond said frame, means connected to said last named links for imparting movement thereto whereby movement may be transmitted through said arms to certain of said breaker members whereby movement will be transmitted through said link interconnecting means and said links to the other of said breaker members to cause said breaker members to be simultaneously moved relative to and through said openings, said last named means including a rocker member, an arm extending from said rocker member, and means associated with said last mentioned arm for locking said arm in predetermined positions to lock said breaker members in predetermined positions relative to said grate sections.

In testimony whereof I affix my signature,
JOHN A. FILBERT.
